UNITED STATES PATENT OFFICE.

CHARLES M. CONNOLLY, OF TROY, NEW YORK, ASSIGNOR TO CLUETT, PEABODY & CO., INC., OF TROY, NEW YORK, A CORPORATION OF NEW YORK.

COLLAR-DISPLAY FORM.

1,395,557.

Specification of Letters Patent.

Patented Nov. 1, 1921.

Application filed November 6, 1920. Serial No. 422,149.

To whom it may concern:

Be it known that I, CHARLES M. CONNOLLY, a citizen of the United States of America, residing at Troy, in the county of Rensselaer and State of New York, have invented new and useful Improvements in Collar-Display Forms, of which the following is a specification.

Reference may be had to the accompanying drawings, and the reference characters marked thereon, which form a part of this specification. Similar characters refer to similar parts in the several figures therein.

This invention relates to forms for displaying collars in stores or show-windows.

The principal object of the invention is to support a plurality of collars attractively displayed for inspection of prospective customers.

Other objects will appear in connection with the following description.

Figure 1 of the drawings is a view in front elevation of a display form embodying my invention.

Fig. 2 is a view in side elevation of the same.

Fig. 3 is a view in rear elevation of the same with the foot and collar-supporting fin folded flatly upon the column.

Fig. 4 is a cross-section of the same taken on the broken line 4-4 in Fig. 2.

Fig. 5 is a similar view taken on the broken line 5-5 in Fig. 3.

Referring to the drawings wherein the invention is shown in preferred form, 1 is an upright or column terminating at the lower end in a supporting base, 2, and at the upper end in a head, 3, which may be of any desired ornamental form.

Mounted upon the back of the column, 1, is a fin, 4, which in use projects rearwardly at right angles to the plane of the column as shown in Figs. 2 and 4.

This fin is formed with a series of hooks, 5, each adapted to receive the back portion of a collar, 6, inserted within the hook with

the collar encircling the column, 1, as shown in Figs. 1 and 2.

The front ends of each collar are preferably secured together by a collar-button, 7. 50

A plurality of collars can thus be supported one above another encircling the column, 1, in position for comparative display to a prospective customer, or in a show window or the like.

For certain purposes of the invention the fin with the hooks, 5, may be constructed in any known manner.

For convenience in transportation however, I prefer to make the fin, 4, foldable, 60 forming the same from a strip of pasteboard or the like creased at 8 along its longitudinal middle, the portion of the strip on one side of the crease forming the fin, 4, while the portion, 9, on the other side of the crease forms an attaching flap which can be glued to the back of the column, 1.

The lower end of the fin, 4, forms a foot, 10, which co-operates with the base, 2, of the column, to form a staple support for 70 the device.

A tongue, 11, is cut out from the strip of pasteboard before the crease, 8, is formed therein, said tongue being adapted to be bent at right angles to the plane of the flap, 9, 75 and being provided with a notch, 12, adapted to engage the fin, 4, when the fin is bent out at right angles to the column, 1, and to support the fin and foot, 10, in position for use.

What I claim as new and desire to secure by Letters Patent is—

A collar display form having an upright member with a rearwardly projecting fin formed with a plurality of hooks adapted to receive the back portions of a plurality of collars supported one above another encircling the upright member.

In testimony whereof I have hereunto set my hand this 3rd day of November, 1920.

CHARLES M. CONNOLLY.
